SHEET STOCK PUNCH HEAD HOUSING

Allan O. Marsh, Los Angeles, Calif.

Application August 7, 1950, Serial No. 178,119

4 Claims. (Cl. 164—91)

1

The present invention relates to an improved paper punch.

The present invention contemplates the provision of novel techniques and structures whereby the punch head housing may be formed of sheet stock, thus eliminating the necessity for the fabrication of castings, forgings and lathe operations as required in the prior practice of manufacture of paper punches.

The present invention, in general, constitutes an improvement on the construction shown in my prior United States Letters Patent 2,587,185, patented February 26, 1952 on an application filed September 17, 1946. The claims in the aforementioned patent are directed generally to an operating rod coating with a punch head, whereas the present application is directed generally, as indicated in the preceding paragraph, to a punch head housing which houses and mounts essential elements for performing a punching operation.

It is therefore an object of the present invention to provide a novel housing of sheet stock which is adapted to include the necessary components for punching holes in paper.

Another object of the present invention is to provide a housing of this character characterized by its inexpensiveness, simplicity and ease of manufacture in accordance with present day mass production techniques.

In general, an object of the present invention is to provide an improved paper punch.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 is a perspective view showing a paper punch embodying features of the present invention;

Figure 2 is a sectional view taken substantially on the line 2—2 of Figure 1;

Figure 3 is a sectional view taken substantially on the line 3—3 of Figure 2; and

Figure 4 shows the general form, not necessarily in proportion, of the stamped sheet stock, in flat form, prior to its being formed as a housing for the component parts of the individual punches shown in the previous figures.

The punch consists essentially of a base member 10 to which is releasably fastened, by means of

2

knurled bolts 16, in spaced relationship, a pair of punch heads 11, 12 with a longitudinally grooved operating rod 13 passing through the individual punch heads 11, 12, such operating rod 13 having affixed thereto a manually operable handle 14, operation of which results in rotation of the operating rod 13 and resulting downward movement of the punch die 15, which is operatively connected to the rod 13 in the manner shown in Figure 2.

The present invention concerns itself particularly with the method of forming the die head housing 18 and resulting structure. Heretofore, the housing for the die member 15 consisted of a relatively expensive casting or forging or other element which required expensive lathe operations in its fabrication. An important feature of the present invention is that such housing 18 is formed of prestamped sheet metal stock.

The sheet stock is stamped to have the general form shown in Figure 4. Such flat sheet 19, shown in Figure 4, is centrally apertured at 19A and is bent back upon itself along generally a line represented by the dotted line 20 in the process of forming the tubular end portions 21, 22 (Figure 3). It will be observed that the cylindrical portion or tube 22, in fact, comprises a pair of vertically aligned tubular sections 22A and 22B.

The movable punching die 15, having an integrally formed annular flange 15A thereon, is mounted for vertical movement in the tubular portion 22A, with the longitudinally extending grooved portion 13A of operating rod 13 partially embracing a peripheral portion of the flange 15A, as shown in Figure 2.

This operating rod 13 passes through circular spaced bearing apertured portions 19C in each of the die heads 12. Such die punch 15 is normally biased upwardly by the coil compression spring 23, having its upper end bearing against the lower flange 15B on the die punch and its lower end bearing against the spring retaining disk 24, which is prevented from leaving the lower end of the tubular portion 22A by deforming the peripheral edges thereof, as for example by crimping, to produce the inwardly extending projecting portions 22D (Figure 3). The lower die punch 25, in the form of a ring, which cooperates with the movable die punch 15, may simply rest on the upper peripheral edge of the lower tubular section 22B, there being, as shown in Figure 2, an annular flange on the die member 25 which prevents the die 25 from falling into the tubular section 22B, and there also being an inner annular

flange portion 25A which cooperates with the inner walls of the lower tubular section 22B to maintain it in centered relationship with respect to the other die member 15.

It is observed that the base 10, to which the die heads are secured, has a recessed ledge 10A contiguous with a transversely extending guide 10B which conforms generally with the shape of the lower bulbous portion 19E' of the housing 18.

Such housing is preferably releasably secured for adjustment purposes to the base 10 by means of knurled bolts 16 but, if desired, may be permanently affixed thereto by rivets which pass through the tubular portion 21 and slotted portion 10C of the base 10. Such slotted portion 10C, as shown in Figure 1, extends transversely of the base 10 in a direction extending parallel with the longitudinal axis of the bulbous portion 10B.

A careful inspection of Figures 3 and 4 shows that the housing 18 formed from the prestamped flat sheet stock 19 is formed to provide the tubular portion 21, the tubular portions 22A, 22B, as well as the circular bearing portion 19C (Figure 2).

The housing 18 thus consists essentially of a double layer of juxtaposed sheet metal material welded together, as for example by welding material 30. Each of such juxtaposed layers have cooperating reentrant portions which define the pair of cylindrical portions 21, 22 having their parallel axes extending generally parallel with the planes of such sheet layers. Also, each of such layers define the paper opening 27 provided by the apertured portion 19A, such reentrant portion 27 (Figure 2) being contiguous with one edge of the juxtaposed layers and extending through the cylindrical portion 22 to divide the same into two vertically aligned cylindrical portions 22A, 22B. The upper tubular section 22A is intersected by a cylindrical portion 19C, having its axis extending generally perpendicular to the axes of the juxtaposed layers provided by the formed sheet 19.

It is evident, from the teachings incorporated herein, that the juxtaposed layers of sheet material shown in Figure 3 may have their ends terminating other than as shown in Figure 3, where such ends 19E, 19F abut on the circumference of the tubular section 21. It is preferred that these ends 19E, 19F abut as shown in Figure 3 instead of on the circumference of the tubular section 22, since the tubular section 22 should be stronger than the tubular section 21. As mentioned above, such tubular section 21 may be clamped either permanently or semi-permanently to the base 10, and when, as preferred, the knurled bolt 16 is used, the housing 18 may be released from the base by loosening the hexagonal nut 33 threaded on the bolt 16.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. In a punch of the character described, a punch head housing comprising: a double layer of juxtaposed sheet stock material, each layer having cooperating spaced reentrant portions which define a pair of cylindrical tubular portions having their parallel axes extending generally parallel with the planes of said sheet

stock material, each of said layers having an apertured portion contiguous with one edge of said juxtaposed layers and extending through one of said cylindrical portions to divide said one cylindrical portion into two vertically aligned spaced cylindrical portions, the upper one of said aligned spaced cylindrical portions being intersected by a third cylindrical portion defined between juxtaposed layers and having its axis extending generally perpendicular to the axis of said one cylindrical portion, a punch die supported for sliding movement in said upper one of said aligned cylindrical portions, said die having a shoulder thereon, an operating rod with a longitudinally extending grooved portion passing through said third cylindrical portion with the grooved portion thereof embracing said shoulder, a spring within said upper cylindrical portion and acting to bias said shoulder up into engagement with said grooved portion of said operating rod, a spring seat against which the lower end of said spring bears, means retaining said spring and spring seat within said cylindrical portion, a second cooperating cylindrical ring-shaped die disposed within the lower one of said aligned spaced cylindrical portions, and means retaining said second die on said lower cylindrical portion.

2. In a punch of the character described, a punch head housing comprising: a double layer of juxtaposed sheet stock material, each layer having cooperating spaced reentrant portions which define a pair of cylindrical tubular portions having their parallel axes extending generally parallel with the planes of said sheet stock material, each of said layers having an apertured portion contiguous with one edge of said juxtaposed layers and extending through one of said cylindrical portions to divide said one cylindrical portion into two vertically aligned spaced cylindrical portions, the upper one of said aligned spaced cylindrical portions being intersected by a third cylindrical portion defined between juxtaposed layers and having its axis extending generally perpendicular to the axis of said one cylindrical portion, a punch die supported for sliding movement in said upper one of said aligned cylindrical portions, said die having a shoulder thereon, an operating rod with a longitudinally extending grooved portion passing through said third cylindrical portion with the grooved portion thereof embracing said shoulder, a spring within said upper cylindrical portion and acting to bias said shoulder up into engagement with said grooved portions of said operating rod, a spring seat against which the lower end of said spring bears, and the lower edge of said upper cylindrical portion being deformed to retain said spring and said spring seat therein, and a second cooperating ring-shaped die disposed within the lower one of said aligned spaced cylindrical portions, and means retaining said second die on said lower cylindrical portion.

3. In a punch of the character described, a punch head housing comprising: a double layer of juxtaposed sheet stock material, each layer having cooperating spaced reentrant portions which define a pair of cylindrical tubular portions having their parallel axes extending generally parallel with the planes of said sheet stock material, each of said layers having an apertured portion contiguous with one edge of said juxtaposed layers and extending through one of said cylindrical portions to divide said one cylindrical portion into two vertically aligned spaced cylindrical portions, the upper

one of said aligned spaced cylindrical portions being intersected by a third cylindrical portion defined between juxtaposed layers and having its axis extending generally perpendicular to the axis of said one cylindrical portion, a punch die supported for sliding movement in the upper one of said aligned cylindrical portions, said die having a shoulder thereon, and an operating rod with a longitudinally extending grooved portion passing through said third cylindrical portion with the grooved portion thereof embracing said shoulder, a spring within said upper cylindrical portion and acting to bias said shoulder up into engagement with said grooved portion of said operating rod, a spring seat against which the lower end of said spring bears, and the lower edge of said upper cylindrical portion being deformed to retain said spring and said spring seat therein, and a second cooperating cylindrical ring shaped die disposed within the lower one of said aligned spaced cylindrical portions, said second die having an annular flange resting on the upper edge of said lower cylindrical portion.

4. In a punch of the character described, a punch head housing comprising: a double layer of juxtaposed sheet stock material formed from a single sheet of material, each layer having cooperating spaced reentrant portions respectively at the center and at the ends of said sheet of material which define a pair of cylindrical tubular portions having their parallel axes extending generally parallel with the planes of said sheet stock material, each of said layers having an apertured portion contiguous with one edge of said juxtaposed layers and extending through one of said cylindrical portions to divide
